ARTIFICIAL ARM

Robert W. Wilkinson, Tisdale, Saskatchewan,
Canada

Application July 23, 1947, Serial No. 762,895

8 Claims. (Cl. 3—12)

1

This invention relates to artificial arms and more particularly to means for operating the same which utilize relative movement between the torso and a shoulder of the wearer.

Artificial arms as developed in the prior art generally are operated through wires or suitable strap means passing across the body or over the shoulders of the wearer to fasten to or to be actuated by his good arm. Such mechanisms are cumbersome, their unwieldy nature leading not only to discomfort of the wearer but also lack of efficiency, particularly with regard to the lifting of objects of any substantial weight.

My invention substantially obviates these disadvantages evident in mechanisms of the prior art by providing an artificial arm which is operable from one side of the body and is independent of the good arm of the wearer for its actuation.

My invention also has for its object the provision of an artificial arm of this class which depends for its operation upon relative movement between the torso and the shoulder carrying the "stump" of the wearer, being hereinafter referred to as the adjacent shoulder.

A further object of the present invention is to provide an artificial arm as before, by virtue of which the wearer is capable of lifting a weight which he might not be capable of handling with his natural arm.

A still further object of the present invention is to provide an artificial arm which is capable of operation by a wearer even though the wearer has no stump.

With these and other objects in view, the invention generally relates to improvements in artificial arms of the class having an upper arm member with a forearm member hingedly connected thereto and leverage means associated with the forearm member adjacent the linkage.

The invention relates to the combination of means for anchoring the upper arm member substantially rigidly to the torso of the wearer by means of a suitable harness or the like and means extending from the leverage means of the forearm member to be anchored to the shoulder adjacent the upper arm member so that the wearer, even though having no "stump," can raise his shoulder relative to his torso and actuate the leverage means to cause swingable rotation of the forearm member relative to the upper arm member. In the embodiments of the invention to be illustrated, the anchorage of the means extending from the leverage means to the shoulder of the wearer is accomplished by employing a shoulder member in the form of a shoulder cover which

5 overlies the end portions of the shoulder so that the shoulder may press in the upward direction. The weight of the forearm member may serve to return it to the normal pendant position, depending upon design characteristics, so that the upper arm member and the forearm member are substantially aligned beside the body of the wearer.

Other objects of the invention will be revealed by a study of the following specification taken in conjunction with the accompanying drawings.

In the drawings—

Figure 1 is a view of an artificial arm fashioned according to my invention with the shoulder member removed, the forearm member thereof being partially cut away to reveal the means employed for mounting an artificial hand, the arm being shown in the "normal" or unbent position. This view is taken in a direction looking toward the inner side of the arm and into a suitable harness device which is used for fastening the upper arm member to the torso of the wearer.

Figure 2 is a plan view of the arm of Figure 1 showing the shoulder member assembled therewith and partially cut away to reveal characteristics of the internal structure. In this figure, portions of the upper arm member and the harness for anchoring the same to the torso are shown in chain lines. From the nature of the disposition of the components, it will be apparent that a right arm is illustrated having the components arranged in a position comparable to a front view of a person having the palm of the hand turned forward.

Figure 3 is a sectional view of one form of gripping means in the form of an artificial hand suitable for use with my invention.

Figure 4 is a sectional view of the wrist portion of the arm of Figure 1, looking in the direction of the arrows 4—4.

Figure 5 is a perspective view of a tool mounting block which may be mounted in the forearm member in place of the artificial hand of Figure 3 to serve as another form of gripping means.

Figure 6 is a more detailed view of the hinge means shown in Figure 2 connecting the upper arm member and the forearm member, being partially cut away to reveal adjusting means whereby the upper arm member, the hinge means, and the forearm member are adjustable relative to one another.

Figure 7 is an enlarged partially cut away view of a portion of Figure 1 showing the hinge means and leverage means along with adjusting means therefor.

Figure 8 is a cutaway perspective view of the

lower end of the shoulder member indicating adjusting means for the same.

Referring now to the drawings, and more particularly to Figures 1 and 2, it will be observed that my artificial arm is comprised of an upper arm member 10 and a forearm member 11 connected by the hinge means 12. The upper arm member 10 is designed to be anchored to the upper portion of the body of the wearer by the body plate 13 which has suitable straps 14 and 15 designed to pass around the body of the wearer and fasten in a conventional manner. A strap 16 is also provided which extends from the body plate 13 to pass over the opposite shoulder of the wearer and which, therefore, must be shaped and fitted according to preference.

A shoulder member sleeve 17 fits slidably within the upper arm member 10 as indicated in Figure 2 and carries a shoulder plate 18 designed to fit over the adjacent shoulder of the wearer. It is assumed, in the design shown, that the wearer has no stump and, of course, it will be appreciated that this does not necessarily limit the use of my invention, for by slight alteration in the design of the shoulder member sleeve 17 it will accommodate a stump of some length. The shoulder member connects by an adjusting rod 19 and a chain or suitable movement transmitting link 20 to the toothed segment 21, the latter being coaxially mounted on the shaft 22 of the hinge means 12, means (to be described hereinafter) being provided in the forearm member 11 for fixing the toothed segment 21 relative to the forearm member. It is thus apparent that axial movement of the upper arm member 17 within the upper arm member 10 will cause swingable movement of the forearm 11 about the shaft 22 relative to the member 10, by means of leverage developed through the toothed segment 21 with the shaft 22 acting as a fulcrum.

Thus a novel method of actuating an artificial arm according to the invention is effected since when the upper arm member 10 is anchored to the torso of the wearer by a body plate 13, it remains substantially immovable relative to his torso. Neglecting for a moment, the structure of the shoulder member of Figure 2, it will be apparent that if one's hand could be inserted into the upper arm member to grasp the adjusting rod 19 which connects to the leverage means involved in the tooth segment 21, then a pulling of this rod would cause the forearm member 11 to swing on the hinge means 12 relative to the upper arm member. According to the invention, means are provided for connecting the leverage means described to the adjacent shoulder of the wearer, such structure involving generally the shoulder member 17 adjustably connectable to rod 19 and which extends to mount the shoulder plate 18 which rests over, and substantially covers, the adjacent shoulder of the wearer. It will be apparent that if adjusting means are provided whereby the wearer can fasten the upper arm member and shoulder member components to his torso and adjacent shoulder respectively so that when the adjacent shoulder is depressed, relative to his torso, and the forearm member is pendent in the normal downwardly hanging position, then upon raising his adjacent shoulder, the shoulder member will be raised upwardly of the upper arm member to cause the forearm member to swingably raise. Not only does the invention herein embody essential structure which takes advantage of this novel method of actuation of an artificial arm, but relates also to a member of

adjustment expedients by virtue of which an artificial arm may be fashioned to more nearly simulate the normal capabilities of the human arm.

5 The free end of the forearm member 11 mounts suitable gripping means 22a as indicated in Figs. 1 and 2, which show an artificial hand, the structure of the latter being more specifically illustrated in Fig. 3. The body of the hand 23 has 10 a mounting block 24 extending therefrom and designed to be accommodated in the receiver 25 of the forearm member 11 and fastened therein by locking screw 26, engaging the depression 26a in the block 24. The body of the hand 23 mounts a 15 swingable thumb member 27 pivoted as at 28, the lever arm 29 of the thumb 27 being connected by a suitable link 30 to a shaft 31 mounted in the block 24 to provide gripping pressure in the thumb by the spring means 32 engaging the 20 washer 33. The adjusting nut 34 riding the threaded portion 35 of the shaft 31 provides a simple and efficient means of adjusting the necessary gripping pressure of the thumb 27 relative to the body 23 of the hand. Suitable finger members 36 extend from the body 23 on either side of the thumb member 27 substantially as indicated in Fig. 2.

Where the operator desires to handle certain specific tools, a block 37 (Fig. 5) may be provided 30 which is designed to be mounted in the receiver 25 instead of the artificial hand formerly described, the form shown having a through bore 38 designed to accommodate the handle of a hacksaw, say (not shown), the latter to be securely held by the locking screw 39. The block 37 has a depression 26b to receive the end of screw 26 and facilitate secure fastening of the block in the receiver 25. It will be appreciated that other designs of blocks may be provided which mount 40 specific tools or, in the alternative, tools may be fashioned having a block portion designed to be received and mounted in the receiver 25.

In order to simulate normal capabilities of the human arm, provision is made for the axial rotation of the forearm member 11 relative to the hinge means 12 and rotation of the hinge means 12 relative to the upper arm member 10. Referring to Fig. 6 these functions will be evident by observing that the forearm member 11 mounts the sleeve 40, the latter being fixed by suitable pins or screws 41. The lower arm portion 42 of the hinge means 12 is in the form of a tapered body 43 which fits slidably into the inner tapered bore 44 of the sleeve 40 and mounts a toothed 50 retaining ring 45 at the inner extremity 46, being fixed by suitable pins 47 and presenting teeth 48 to the locking dog 49 to constitute adjustable detent means. Relative rotation between the lower arm portion 42 of hinge means 12 and the 55 forearm member 11 is accomplished through releasing the dog shaft 50 by pulling on a cord (not shown) attached to the draw ring 51 (Fig. 7) against the pressure of spring means 52 and rotating the forearm member 11 to the desired position 60 and releasing the dog shaft 50 to allow the dog 49 to engage the teeth 48. It will be apparent that the rotation of the forearm member relative to the hinge means 12 is a matter of adjustment only and that the arm remains fixed 65 in a selected position of adjustment. To adjust the arm to a different attitude, with regard to the rotative means discussed, the operator with his good hand may draw on a cord attached to the draw ring 51 and, by holding the forearm 70 member between his knees, adjust to another

position of desired adjustment. In some instances, the amputee may require help to adjust his arm.

Similar rotative adjustment is provided in the upper arm member 10, the latter mounting a similar sleeve 53 by suitable screws 54, the upper arm portion 42a of the hinge means 12 being accommodated in the tapered bore 55 and being held therein by the toothed retaining ring 56 fixed to the inner end 57 of the upper arm portion 42a by suitable pins 58. The teeth 59 of the ring 56 are engaged by a dog 60 having a flexible type shaft 61 communicating to an exterior ring 62 which may be pulled by the good arm of an operator against the pressure of spring means 63. Thus by pulling on the ring 62 the operator may release the dog 60 and rotate the upper arm portion 42a of the hinge means 12 relative to the upper arm member 10 to a new position of adjustment and thereafter release the ring 62 to allow the dog 60 to engage the teeth 59, to provide a locking function. As shown, the teeth formed on both the toothed retaining ring 45 and the ring 56 extend only half way around the circumference of each, providing, in the ultimate, 360° of adjustment in the gripping means and substantially 180° of adjustment in the hinged means relative to the upper arm member. The operator, with his good hand, may pull on the ring 62 to provide rotative adjustment of the hinge means 12 relative to the upper arm member 10 somewhat in the manner discussed with reference to the adjustment of the forearm member previously described. Therefore, to the extent that the arm may be adjusted for different attitudes concerning the disposition of the hinge means 12 of the elbow relative to the upper arm member and the rotative adjustment of the forearm member and hand relative to the hinge means of the elbow, the artificial arm of my invention is simulative of the capabilities of the human arm.

As will be apparent from Figs. 6 and 7 the hinge means 12 are comprised of the bifurcated arms 64 extending from the lower arm portion 42 and the bifurcated arms 65 extending from the upper arm portion 42a, being mounted on the common shaft 22 which also mounts the toothed segment 21, the latter being disposed between the bifurcated arms 64 (Fig. 7). Suitable teeth 67 are provided on the periphery of the toothed segment 21 and are engaged by a toothed dog 68 slidably mounted in the bore 69 of the lower arm portion 42 of hinge means 12. A portion of the bore 69 is threaded as at 70 to carry a bushing 71 which slidably mounts a shaft 72 having actuating means 73 extending outwardly of the arm to present an actuating ring 74 to an operator. The other end of the shaft 72 is thread mounted in the dog 68 as at 75, positive engagement with the dog 68 with the teeth 67 of the toothed segment 21 being ensured by a suitable spring 76. Various positions of engagement of the dog 68 with the teeth 67 are therefore possible providing a means of adjusting the sweep limits of the forearm members relative to the upper arm member.

In order to provide a means for returning the forearm member to "normal" position, the latter being determined according to the segment adjustment (i. e. the engagement of the dog 68 with the teeth 67 of the toothed segment 21) an opposed compression spring 77 is provided and mounted on a shaft 78 which is pivotally connected as at 79 to the extended arm portion 80 of the toothed segment 21. The shaft 78 extends loosely through the bore 81 of the upper arm por-

tion 42a of hinge means 12, spring means 77 engaging the abutment 82 and being confined by the washer 83 and pin 84 at the free end of the shaft 78.

Referring to Figs. 1, 2, 7 and 8 it will be observed that adjusting means are provided in the shoulder member whereby the relative distance between the operating position of the shoulder of the wearer relative to the fastening position of the body plate to the upper portion of his body may be adjusted to vary the normal rest position of the forearm member relative to the upper arm member, that is the position when hanging freely at the side of the wearer. Thus, in Fig. 2 it will be noted that the link 20 extending from the pivot point 21a on the toothed segment 21 connects to the bifurcated arms 19a of the adjusting rod 19 by a suitable pin 85, the latter rod passing through a bore 86 in the closed end 87 of the shoulder member sleeve 17. A gear 88 suitably threaded for reception on the threaded shaft 19 (see Fig. 8) serves as a means for adjusting axial position of the rod 19 through the worm adjusting means 88a which may be rotated by a suitable key engaging the stud end 89 which is accessible through a slot 90 in the sleeve 17 and a further slot (not shown) in the upper arm member 10. Free slideable travel of the sleeve 17 is insured by rollers 17a (Figure 2) mounted in brackets 17b fixed to the inner surface of the sleeve 17. The rollers 17a extend through orifices 17c to engage the inner surfaces of the upper arm sleeve 53.

It will be appreciated that through the various adjusting means provided, an artificial arm fashioned according to my invention will be capable of movement simulating the capabilities of the human arm. Further, due to the use of a body plate and cooperating shoulder member wherein advantage is taken of relative movement between a shoulder of the wearer and the upper portion of his torso, the present device is operable from one side of the body only. As previously discussed, the upper arm member remains at all times substantially fixed relative to the torso of the wearer so that in the structural arrangement described, the wearer merely presses upwardly on the shoulder plate 18 against the weight of the forearm member. If the shoulder is raised with the body, as would probably be the normal tendency of a person first wearing the device, the forearm member will not be actuated. The wearer must learn to move his shoulder relative to his torso somewhat in the manner which is observed when a person "hunches" his shoulders but, in this instance, only one shoulder is involved. The "hunching" is done against the weight being lifted. The human body is capable of developing a large force in the relative manner described and when this principle is applied to the operation of an artificial arm as shown it has been found that weights largely in excess of those which could be lifted by the human arm only with difficulty, may be lifted with comparative ease. Moreover, in view of the fact that operation is dependent upon movements related to one side only of the body of the wearer, the latter's good arm will be free for efficient cooperation with the artificial arm. It may also be pointed out that the weight of the arm is partially supported by the shoulder member which, due to the design shown, substantially avoids the discomforts of chafing and cutting of numerous straps resulting from the wearing of artificial arms of the prior art.

It is apparent that modifications may be effected in the specific design of the shoulder member and its cooperation with the upper arm member from the particular form shown, since changes will be necessary to meet the requirements for various amputees. It is therefore intended that the present disclosure should not be limiting in any way other than that indicated by the scope of the following claims.

What I claim as my invention is:

1. An artificial arm comprising an upper arm member, means for anchoring said upper arm member to the torso of an amputee in a position corresponding to the location of the upper portion of the severed arm and in a substantially fixed position with regard to the torso, a forearm member pivotally connected to said upper arm member in simulation of an elbow joint, a shoulder plate mountable on the adjacent shoulder of the amputee, leverage means connectable to said forearm member for movement therewith about said pivoted connection, and movement transmitting means connecting said leverage means and said shoulder plate, whereby upward movement of said shoulder is transmitted by said movement transmitting means to said leverage mechanism and forearm member to cause movement of said forearm about said hinged connection relative to said upper arm member.

2. An artificial arm comprising an upper arm member, a forearm member, hinge means operatively connecting the upper arm member to the forearm member, means for fastening the upper arm member to the torso of the wearer to hold said member substantially fixed with regard to the torso, leverage means for actuating the forearm member about said hinge means and having a fulcrum coincident with the axis of said hinge means, shoulder engaging means mountable on the adjacent shoulder of the wearer, and movement transmitting means connected to said shoulder engaging means and attached to said leverage means at a point spaced from said axis, whereby relative movement between said shoulders of the wearer and his torso causes swingable movement of the forearm member relative to the upper arm member about said axis.

3. An artificial arm as claimed in claim 2, and adjustable detent means mounted on said forearm member and engageable with said leverage means for adjusting the sweep limits of said swingable movement of the forearm member relative to the upper arm member.

4. An artificial arm as claimed in claim 2, adjustable detent means providing rotative adjustment of the forearm member relative to the hinge means, and second adjustable detent means providing rotative adjustment of the hinge means relative to the upper arm member, whereby the forearm member is capable of rotatable adjustment to simulate various attitudes of the human arm.

5. An artificial arm as claimed in claim 2, means providing rotative adjustment of the forearm member relative to the hinge means, means providing rotative adjustment of the hinge means relative to the upper arm member, said rotative adjusting means for the forearm member comprising a toothed retaining ring operatively connectable to the hinge means, a tapered sleeve forming the outer portion of the forearm member and rotatable relative to the toothed retaining ring and hinge means, and a spring retained dog carried by said tapered sleeve and engageable with the toothed retaining ring to hold the latter

in a desired position of rotative adjustment relative to the sleeve, and the said rotative adjusting means for the upper arm member comprising a second toothed retaining ring connected to the hinge means, an outer cylinder forming the outer portion of said upper arm member and rotatable relative to said second toothed retaining ring, and releasable means carried by said outer cylinder and adapted to engage the teeth of said second ring for fixing the second ring in a selected position of rotative adjustment relative to said outer cylinder.

6. An artificial arm comprising a forearm member, an upper arm member, hinge means providing a hinged connection about a hinge axis between said two members, a body plate attached to said upper arm member, means for securing said body plate to the torso of the wearer in a substantially fixed position with respect to the torso, a leverage segment coaxial with said hinge means, means interconnecting said leverage segment with said forearm member to cause said forearm member to move with said leverage segment, a shoulder member mountable on the adjacent shoulder of the wearer for movement with said shoulder, linkage means connecting said shoulder member with a first portion of said leverage segment spaced from said hinge axis for causing movement of said leverage segment and said forearm member about said hinge axis relative to said upper arm member when said shoulder is raised with respect to said body plate and upper arm member, and resilient means mounted between a second portion of said leverage segment and said upper arm member in opposition to such movement of the leverage segment and forearm member.

7. An artificial arm as claimed in claim 6 in which said shoulder member comprises a sleeve, a shoulder plate attached to the upper end of the sleeve, and an apertured closure at the lower end of the sleeve, said linkage means including an adjusting rod passing through said apertured closure and operatively connected to said first portion of said leverage segment, and means for adjustably fixing the amount of protrusion of the adjusting rod through the apertured closure to vary the normal rest position of said forearm member relative to the upper arm member.

8. An artificial arm comprising a forearm member, an upper arm member, hinge means providing a hinged connection about a hinge axis between said two members, a body plate attached to said upper arm member, means for securing said body plate to the torso of the wearer of the arm in a substantially fixed position with respect to the torso, a leverage segment coaxial with said hinge means, means interconnecting said leverage segment with said forearm member to cause said forearm member to move with said leverage segment, a shoulder member mountable on the adjacent shoulder of the wearer for movement with said shoulder, linkage means connecting said shoulder member with a first portion of said leverage segment spaced from said hinge axis for causing movement of said leverage segment and said forearm member about said hinge axis relative to said upper arm member when said shoulder is raised with respect to said body plate and upper arm member, and resilient means mounted between a second portion of said leverage segment and said upper arm member in opposition to such movement of the leverage segment and forearm member, said shoulder mem-

ber comprising a sleeve, a shoulder plate attached to the upper end of said sleeve, and an apertured closure at the lower end of the sleeve, said linkage means including an adjusting rod having a threaded portion and passing through said apertured closure, means connecting said rod to said first portion of said leverage segment, and means for adjustably fixing the amount of protrusion of said adjusting rod through the apertured closure in the direction of the hinge to 10 vary the normal rest position of said forearm member relative to the upper arm member, said last named means comprising a nut having peripheral teeth and rotatably mounted on said threaded rod portion, said nut being positioned 15 adjacent said closure to limit movement of said rod in the direction of said hinge, and a rotatable worm adapted to articulate with said teeth to provide means for rotating the nut on said rod,

whereby the length of rod protruding from said closure in the direction of the hinge is variable by rotation of said worm.

R. W. WILKINSON.
